(57) **CLAIM**

We claim the ornamental design for a fluid dispenser support, as shown and described.

DESCRIPTION

FIG. 1 is a front right perspective view of a fluid dispenser support in an open position showing our new design;
FIG. 2 is a front right perspective view of a fluid dispenser support in a closed position;
FIG. 3 is a top view thereof;
FIG. 4 is a bottom view thereof;
FIG. 5 is a front view thereof;
FIG. 6 is a right side view in a closed position; and,
FIG. 7 is a partial right side sectional view thereof, taken along line 7—7 of FIG. 1.
